(57) **CLAIM**

The ornamental design for a portion of a display panel with an indicator icon, as shown and described.

DESCRIPTION

The FIGURE is a front view of a portion of a display panel with an indicator icon shown in the environment of a pulse oximetry monitor, where the triangular indicator is empty. The broken line showings of the portion of the display panel and various regions therein are included for the purpose of illustrating portions of the portion of a display panel with an indicator icon and form no part of the claimed design.
